UNITED STATES PATENT OFFICE.

OLIVER H. CLARK, OF DETROIT, MICHIGAN.

DESIGN FOR A COMBINED COWL AND WINDSHIELD.

Application filed April 7, 1928. Serial No. 26,164. Term of patent 3½ years.

To all whom it may concern:

Be it known that I, OLIVER H. CLARK, a citizen of the United States, residing in the city of Detroit, in the county of Wayne and State of Michigan, have invented a new, original, and ornamental Design for Combined Cowl and Windshield, of which the following is a specification, reference being had to the accompanying drawing, forming a part thereof, in which:

Fig. 1 is a front elevation of a combined cowl and windshield assembly for an automobile.

Fig. 2 is a side elevation of Fig. 1.

Fig. 3 is a top plan view.

I claim:

The ornamental design for a combined cowl and windshield, as shown.

OLIVER H. CLARK.
